ATTORNEY

UNITED STATES PATENT OFFICE.

ALBERT L. LAMBERT, OF PHILADELPHIA, PENNSYLVANIA, ASSIGNOR TO HEINTZ MANUFACTURING COMPANY, OF PHILADELPHIA, PENNSYLVANIA, A CORPORATION OF PENNSYLVANIA.

DOOR.

Application filed January 26, 1926. Serial No. 83,955.

This invention relates to doors, and more particularly relates to sheet metal doors for automobile bodies of the closed type.

The principal aim of this invention is to provide a sheet metal door for automobile bodies of the closed type, and to provide a door which is sturdy and durable and at the same time is light in weight and inexpensive and simple in construction. Other objects 10 of my invention will be in part obvious and in part pointed out hereinafter.

In accordance with my invention, the outer panel of the door and the vertical rails are made in one piece from a single sheet of 15 sheet metal, and preferably by means of simple and uncomplicated stamping operation. The construction is reinforced transversely by means of a tube anchored at its opposite ends to the opposite vertical rails. 20 This tube renders the door very sturdy and rigid and braces the construction against distortion from torsional or other strains to which the door is subjected during ordinary use. To provide a glass run for a window, 25 I attach a channel member to each vertical rail at intervals.

In order that a clearer understanding of my invention may be had, attention is hereby directed to the accompanying drawings, 30 forming a part of this application and illustrating certain possible embodiments of my invention.

Referring to the drawings, Fig. 1 is a front view of the door, with a lower edge 35 broken away, and certain hidden features of the construction being shown in dotted lines; Fig. 2 is an end view of the door, showing in dotted lines the internal location of certain of the parts; Fig. 3 is a broken horizontal sectional view through the upper part of the door, and is taken on the line 3—3 of Fig. 1; Fig. 4 is a broken horizontal sectional view through the center of the door, and is taken on the line 4—4 of Fig. 1; Fig. 45 5 is a vertical sectional view of a fragment of the door at the center, and is taken on the line 5—5 of Fig. 1; and Figs. 6, 7, 8 and 9 are each sectional views of different edge portions of the door, and are taken, respectively, on the lines 6—6, 7—7, 8—8 and 9—9 of Fig. 1. Similar reference characters refer to similar parts throughout the several views of the drawings.

Referring to the drawings, the door com-

prises a lower front panel 1 extending from 55 edge to edge of the door, and from the bottom to the lower edge of the window opening 2 and front panels 3 at each side of the window opening, and extending to the top of the door, the panels 1 and 3 being made 60 in one piece and preferably of sheet metal. At the hinge edge of the door, this sheet metal piece is doubled back on itself to provide the overhanging door flange 4, then extends rearwardly, as at 5, then inwardly, as 65 at 6, and then forwardly, as at 7, forming a vertical hinge rail extending the full height of the door. At the opposite edge of the door, the sheet metal piece is doubled back upon itself to form the overhanging flange 70 8, then has a rearwardly extending portion 9 conforming to the shape of the door post, either straight or stepped, then bent inwardly, as at 10, and then forwardly, as at 11, forming the other vertical rail of the door 75 and extending the full height thereof. It will be noted that each of these rails is channel-shaped in cross-section, and it will be recognized that this formation yields a very 80 rigid, sturdy and durable construction. At the lower edge of the window opening, the sheet metal piece is bent inwardly, as at 12. The inner edge of this portion 12 may be reinforced by an angle strip 13, which also serves, in combination with another strip 85 14, as means for retaining a strip 15 of flexible material in position against the glass pane 16 of the window.

Across the center of the door is located a sturdy reinforcing tube 17, which is anchored at each end to reinforcing plates, which in turn are securely attached to the vertical door rails. At the hinge rail, the reinforcing plate 18 is angle-shape, and abuts and is secured to the walls 5 and 6 of 90 the rail. At the opposite edge of the door, the reinforcing plate 19 is of Z-shape, because on this edge the rail is stepped. The rear portion of member 19 abuts and is secured to the rail portion 10. The body portion of member 19 abuts and is secured to the main portion 9 of the rail, and at the front, reinforcing plate 19 meets rail portion 9 edgewise and is secured thereto, as 95 at 20.

To provide a channel for the glass run on each rail, I attach a suitable sheet metal channel strip 21 in place by means of angle

plates or brackets 22, which have one leg seated against and secured to the rail portion 5 or 9, and have the other leg abutting and secured to the outside of one of the side walls of the channel members, as at 23. Preferably, an open joint is left between the other side walls of the channel members and the adjacent rail portions 7 and 11, at the lower part of the door. Above the window opening, however, these channel glass run members may be secured to inwardly bent edge portions of the front panel portions 3 and to the rail portions 7 and 11, as by welding.

15 Across the lower edge of the door on the inside is a sheet metal panel 24, which at its lower edge extends forwardly, as at 26, forming the bottom of the door, and is broken off downwardly along its forward edge, as at 27, and there engaged between the doubled-over lower edge 28 of the panel 1, whereby these panels are anchored together at this location, and the overhanging flange across the lower edge of the door is formed.

25 A plate 30 may be secured across the inside of the door at the center to support suitable window operating mechanism and upholstery, which it is not deemed necessary nor proper to illustrate. The panel 24 is channel-shaped at its upper end, as at 25, to extend to the window runway.

30 To enhance the attractive appearance of the door, the panel 1 may be pre-formed with a transverse bead 31.

35 The top of the door may be completed by extending two sheet metal strips 32 and 33 thereacross, and securing them at their ends to the vertical rails. As shown, one of these members 32 may have a top portion 34 extending from the rear to the front of the door, thus closing the door at the top. If desired, however, the top of the door may be left open.

40 From the above, it will be apparent that by making the outer paneling in one piece with the vertical side rails, and of a single piece of sheet metal, that simplicity of construction and economy of material and labor in manufacture are obtained. By reason of the flanges at the door edges, the channel-shaped formation of the vertical rails, and the tubular reinforcement and bracing, the door is extremely sturdy and durable. At 45 each side of the window opening, a closed box formation is obtained, which is well known to be extremely strong and not readily bent or twisted out of shape. The glass run for the window is formed by very simple and few parts, which may be put in place quickly and easily. Further, the construction does not require the application or use of any screws or bolts, and although welding is employed, the construction is so arranged that no welding marks will appear

50 on visible surfaces of the door. The presence of such marks would detract from the attractive appearance of the structure.

55 As many changes could be made in the above construction and as many apparently widely different embodiments of this invention could be made without departing from the scope thereof, it is intended that all matter contained in the above description or shown in the accompanying drawings shall 60 be interpreted as illustrative and not in a limiting sense.

65 What I claim is:—

70 1. In a door of the character described having a window opening, a channel shaped glass runway member positioned at the side of the window opening, and a one piece sheet metal door rail member extending from one side wall of said channel member around the closed side to the other wall thereof, said glass runway being seated completely within the rail member and being secured to the opposite overlapping edges of the rail member.

75 2. In a door of the character described having a window opening, a channel shaped glass runway member positioned at the side of the window opening, and a one piece sheet metal door rail member extending from one side wall of said channel member, around the closed side, to the other wall thereof, the ends of said door rail member overlapping and rigidly secured to the edges of said channel member, said members constituting a tubular post construction at the side of the window opening, said rail member having an integral overhanging closure flange 80 portion.

85 3. In a door of the character described having a window opening, a channel-shaped glass-run member positioned at the side of the window opening, and a one-piece sheet metal door rail member extending from one side wall of said glass-run member, around the closed side, to the other wall thereof, forming a tubular post construction at the 90 side of the window opening, said glass-run member being seated completely within the rail member and secured at its flange edges to the opposite edges of the rail member.

95 4. In a door of the character described having a window opening, a channel-shaped glass-run member positioned at the side of the window opening, and a one-piece sheet metal door rail member extending from one side wall of said glass-run member around the closed side to the other wall thereof, said members being rigidly secured together to form a tubular post construction at the side of the window opening, and said glass-run member being seated completely within the rail member and being secured at its mouth to the opposite edges of the rail member.

100 5. In door construction of the character described, a door rail member comprising a single piece of sheet metal flanged and

shaped to form complementary window moldings, inner and outer paneling at the side of the window opening, and a door edge wall, and a window runway member completely enclosed within the rail member and bridging and secured at its mouth to the edges of the complementary window molding portions.

6. In a door of the character described, 10 having a window opening, of a single piece of sheet metal having a panel portion extending across the door from the window opening to the bottom of the door beneath the window and a window molding portion 15 at the bottom of the window opening, said piece of sheet metal having also rail portions extending along each side of the window, each rail portion being flanged and shaped to form complementary window moldings 20 and inner and outer paneling at the sides of the window opening, said single piece of sheet metal having also a continuous door edge wall portion and a marginal door closure flange extending the full height of 25 the door along each edge thereof.

7. In a door of the character described having a window opening, a channel shaped glass runway member positioned at the side of the window opening, and a one piece sheet 30 metal door rail member extending from one side wall of said channel member around the closed side to the other wall thereof, said glass runway being seated completely within the rail member and being secured to the opposite edges of the rail member, said rail member having an integral overhanging 35 closure flange portion.

8. In a door of the character described having a window opening, a one piece sheet 40 metal front panel comprising a lower panel portion and upper door rail portions one disposed on each side of said window opening, said front panel having an overhanging

closure flange formed at its bottom and side edges and integral therewith, the side edges 45 of said lower panel portion being bent to form tubular posts, said posts having inner panel portions and moulding portions, the upper edge of said lower panel portion being inturned to form a window moulding, 50 and said upper door rail portions being flanged and shaped to form complementary window mouldings and inner and outer paneling at the side of the window opening.

9. In a door of the character described 55 having a window opening, a one piece sheet metal front panel having a lower panel portion, the upper edge of said lower panel portion being inturned to form a window moulding, an angular shaped member secured along the lower edge of said window moulding portion one flange thereof extending downwardly, a bar disposed in parallelism to said downwardly extending flange, and a filling strip seated between said bar 60 and said angle member, the upper edge of said filling strip adapted to frictionally engage the window glass.

10. In a door of the character described, in combination, a single piece of sheet metal 70 including a panel portion and a door edge wall portion, an angle plate having one leg secured to said edge wall portion, and a channel shaped glass run member suspended to the other leg of said angle plate. 75

11. A door for motor vehicles including, in combination, a single piece of sheet metal including a panel portion and door edge wall portions, reinforcing plates secured to the interior surface of said door edge wall portions, and a reinforcing tube horizontally disposed along the jamb side of the door with its ends secured to said plates. 80

This specification signed this 19th day of January, 1926.

ALBERT L. LAMBERT.
